UNITED STATES PATENT OFFICE.

FERDINAND MILLER, OF SAN FRANCISCO, CALIFORNIA.

KITCHEN-CABINET.

SPECIFICATION forming part of Letters Patent No. 767,908, dated August 16, 1904.
Application filed October 21, 1903. Serial No. 177,918. (No model.)

To all whom it may concern:

Be it known that I, FERDINAND MILLER, a citizen of the United States, residing at San Francisco, county of San Francisco, and State 5 of California, have invented certain new and useful Improvements in Kitchen-Cabinets, of which the following is a specification.

My invention relates to kitchen-cabinets, and more especially to that class employing 10 stoves for cooking; and the object of the invention is to provide a cabinet handy and convenient to the user and which will look neat and is easily kept clean.

The invention consists of a box-like body of 15 rectangular form in cross-section, which body is divided into two sections forming upper and lower compartments, the former of which is adapted to receive cooking-stoves and the latter of which is provided with drawers sliding 20 in ways formed in the interior of the body.

The invention further consists in the novel features and combination of parts, which will be more fully described hereinafter and pointed out in the appended claims.

The drawings which form a part of this application are explained as follows: Figure 1 is a perspective view of the device as it looks closed up. Fig. 2 is a vertical section taken on line $\alpha\alpha$ of Fig. 1. Fig. 3 is a front perspective of the device with the top thrown back and pan and pot drawers partially drawn out. Fig. 4 is a rear and side perspective showing the towel-rack in repose. Fig. 5 is a front elevation of a modified form; Fig. 6, 35 a detail perspective of the same with top closed, and Fig. 7 is a detail perspective of the catch.

Referring more especially to the drawings, 1 represents the body or casing, supported on 40 suitable casters and provided with a double top 2, hinged at 3 to the body, and which top constitutes the upper compartment. The other or lower compartment is divided from the upper one by a horizontal partition 4, which affords a support for the base 5 of member of oil or gas stove 6. Centrally through 45 the lower compartment is positioned a vertical partition 7, with cleats 8. Similar cleats are provided for each side of the body, and 50 on these cleats drawers 9 for the reception of

pots, pans, &c., run. This lower compartment is closed by doors which conceal the drawers. In the upper forward part of the upper compartment is a small box-like case 10, running the entire width of the body, for the 55 reception of soap, bath-brick, and other kitchen necessities. Just back of the stove 6 is a compartment 11, supported on brackets 12, forming the sides of the compartment, and which is provided with hooks 13 in its top arranged to hang dish-cloths upon, and underneath is made a receptacle for placing anything in out of the way, such as kitchen-spoons, soap-shaker, &c. Extending up from the top of the compartment 11 is a back 14, 60 which is raised above the double top 2 and forms one side of a receptacle to receive the towel-rollers 20. Immediately back of the back 14 are a plurality of dowels 15, which 65 form the other side of the receptacle for the towel-rollers 20. Secured to the outside of compartment 11 at its sides are a number of guides 16, in which slide the towel-rack rods 17. The rods 17 are provided at their upper 70 ends with arms 18, notched at 19 along their entire length for the ends of towel-rollers 20, and are adapted to lie when in normal position, as shown in Fig. 4, along the back of the dowels 15. The rods 17 are also provided with holes 21, which are adapted to register 75 with holes 22 in the guides 16 when the rods are extended, as shown in Fig. 3, and to be locked in such extended position by a pin 23, 80 flexibly secured to the outside of the compartment 11. The rods 17 are half-round and half-square, as shown in cross-section, Fig. 4, so as to enable them to turn in the guides 16. A pipe 24, having an open end and extending 85 under the stove-base 5 into the case 10, is provided to take off any dirt that may accumulate and also to carry off any water which may boil over from the pots on the stove through an opening 25. This pipe is provided at its outer end with a screw-cap 26, which prevents the water from continually dripping on the 90 floor. The upper compartment, including the double top and compartment 11, is lined throughout with a metallic lining 27, so that 95 it may be easily kept clean.

In the modified forms (shown in Figs. 5, 6, 100

and 7) the top 28 is used instead of the double tops heretofore shown. This top 28 is hinged to the body at 29 and is provided with an open end 30, which is adapted to be closed by an end flap 31, hinged to the opposite side of the body from that to which the top is hinged. Projecting from one end of the end flap 31 is a stud 32, on which is journaled a peculiar form of catch 33. This catch is adapted to slide in a notched opening formed in the bracket 12. The co-operation of the notch with the catch adapts it to hold the end flap 31 to close the open end of the top or to assume a horizontal position and in such position may be used as a table. The top when in open position is adapted to be used the same as the double tops.

Having thus described my invention, what I claim as new, and desire to secure by Letters Patent, is—

1. A kitchen-cabinet comprising a body, a compartment secured to the back of said body, and a top hinged to said body, the side of which is adapted to close the front of said compartment.

2. A kitchen-cabinet comprising a body having upper and lower compartments, a compartment within said upper compartment, a compartment back of said upper compartment and separated therefrom, and a double box-like top hinged to said body and adapted to close all of said upper compartments.

3. A kitchen-cabinet comprising a body having upper and lower compartments, drawers slidably mounted in said lower compartment, double box-like tops hinged to said body and adapted to fold over said upper compartment and to close the same, said box-like top also adapted to form a table and receptacle for holding kitchen utensils, when opened.

4. A kitchen-cabinet comprising a body having upper and lower compartments, drawers

slidably mounted in said lower compartment, doors closing said lower compartment, double box-like tops hinged to said body and adapted to cover said upper compartment, the ends of said double top adapted to support themselves against the sides of the body when opened, and forming a table for the reception of kitchen utensils.

5. A kitchen-cabinet having a body comprising upper and lower compartments, a compartment back of said upper compartment, hooks in the top of said last-named compartment for hanging articles upon, and means for closing said upper compartment, said means separating the compartment in the back.

6. In a kitchen-cabinet, the combination with a body, of brackets secured to said body and forming the sides of a compartment, a back for said compartment, members forming top and bottom of said compartment, and a double top hinged to said body, the sides of said top adapted to close the front of said compartment.

7. A kitchen-cabinet comprising a body having a compartment, a compartment in rear of said body-compartment, and a double top hinged to said body the sides of which are adapted to close said rear compartment.

8. A kitchen-cabinet comprising a body having a compartment, a top hinged to said body and adapted to close the compartment on three sides, and means hinged to the body and adapted to close the remaining side, said top and said means adapted to form tables when opened.

In testimony whereof I hereunto affix my signature in presence of two witnesses.

FERDINAND MILLER.
